UNITED STATES PATENT OFFICE.

ALBERT J. HADERT, OF NEW ROCHELLE, NEW YORK.

BINDING AND WRAPPING MACHINE.

1,235,313.

Specification of Letters Patent. Patented July 31, 1917.

Original application filed July 5, 1912, Serial No. 707,940. Divided and this application filed October 15, 1912, Serial No. 725,934. Renewed May 25, 1916. Serial No. 99,903.

To all whom it may concern:

Be it known that I, ALBERT J. HADERT, a citizen of the United States, residing at New Rochelle, in the State of New York, have invented certain new and useful Improvements in Binding and Wrapping Machines; and I do hereby declare the following to be a full, clear, and exact description of the invention, such as will enable others skilled 10 in the art to which it appertains to make and use the same.

The present application is a division of my pending application filed July 5th, 1912, Serial No. 707,940, wherein there was described an entire machine whereby loaves of bread or other articles are successively wrapped and bound up or tied automatically. In the aforesaid original application, I have claimed the wrapping units, and in 20 the present divisional application is described and claimed the binding unit.

It is to be understood that the mechanism herein described and claimed is preferably combined with mechanism which first applies and then folds paper or the like around the successive articles, and that the articles so treated are then delivered to the binding mechanism herein described by automatic means, as for instance a moving belt. The 30 invention is, in some respects, broad enough to cover mechanism fed by hand, instead of automatically.

A preferred embodiment of the present invention is shown in the accompanying drawings wherein Figure 1 is a side elevation showing the principal elements of the device, Fig. 2 is an end elevation of the same, Fig. 3 is a plan view of the ribbon-supplying means and gumming device, Fig. 4 is a partly sectional view of the gumming device, Fig. 5 is a perspective of the ribbon gripper, Figs. 6 and 7 show in plan certain portions of the gumming device in the binding unit, Fig. 8 shows the traveling frame 40 for the ribbon conveyer, partly in elevation and partly in section, Fig. 9 is an elevation of the compressing mechanism, Fig. 10 is a similar view of one of the ribbon-securing mechanisms, Fig. 11 is a perspective view of the compressing plate and shaft, and Fig. 12 is a similar view of a ribbon-securing plate with its lifting stem.

It is to be understood that the proportions

of parts, the precise forms and positions of cams and like details as actually shown in 55 the drawings hereto attached, are not intended as guides to a builder. These are details within the skill of the calling. The drawings merely illustrate the principles of my invention in its various aspects, and in 60 connection with a preferred embodiment of those principles.

It is to be understood that the loaf or other article has been wrapped with a suitable flexible material, preferably paper, and 65 is conveyed to the binding unit of a general machine upon a suitable conveyer, such as the belt 20. This belt may move between guides 21, on a rigid support, 22, and it preferably carries the article 23, within a 70 carrier or cradle 24 of suitable construction.

In the preferred form of my invention, one embodiment of which is illustrated herein, the binding unit comprises a ribbon conveyer, a tension device, and a gumming 75 device, as secondary units. To these I prefer to add a package compressor, where it is intended to wrap loaves of bread or other articles or packages capable of compression.

After the package comes to rest, with the 80 last fold naturally slightly inclining outward, as shown in Fig. 2, the package compressor comes into action. In order to surely permit passage along the machine of the last paper folds, however much they 85 may incline outward, I prefer to have that part of the compressor which comes in contact with the package normally occupy a depressed position. For this reason the compressor comprises a preparing means and a 90 compressing mechanism.

The preparing means comprises, in its preferred form a lifting bar 25 carrying rods 26 at its outer ends, which rods are adapted to slide through guides 27. The 95 rods 26 carry at their upper ends horizontal sleeves 28 through which slide the rods 29 normally held outward by springs 30 and carrying at their inner ends compression plates 31 each of which is preferably provided with a ribbon-guiding projection 32. The lifting bar 25 is supported on a stem 33 resting on a preparing cam 34 on the main shaft, whereby the sleeves and plates are lifted into operating position at the 100 proper moment, as shown in Fig. 9. I pre-

fer to use a spring 35 to draw the bar 25 downward, and keep the roller at the lower end of the stem 33 firmly in contact with the cam 34.

5 As soon as the preparing means just described have acted to bring the plates 31 to the proper level on each side of the article 23, the compressing mechanism proper, of which said plates and the rod 29 are a part, 10 comes into play. The other portions of the compression mechanism are the compressing levers 36, pivoted at 37 and supplied with arms 38 to which are pivotally connected the compression rods 39. These rods converge 15 upon a stem 40 to which they are pivoted, which stem is lifted at the proper time by the compressing cam 41, on the main driving shaft. This action causes the upper ends 20 of the levers 36 to push the rods 29 inward from the two sides simultaneously, thus compressing the wrapped package between the plates 31, as shown in Fig. 9.

This compression is gaged by the nature 25 of the package and the wrapping material. Its object is to subject these elements as a 30 whole to such a pressure during the binding operation that, when the pressure is withdrawn the natural resilience of the entire package will cause it to swell within the ribbon, and thus insure this last being tightly 35 and securely applied.

While the operations above described have 40 been preparing the package for its binding, the ribbon conveyor has begun to operate. This secondary unit is preferably composed 45 of a "ribbon feed", a "ribbon grip", a "grip carrier", a "guiding track", and "grip operators"; and the preferred details of construction of these parts are shown in the drawings.

The binding ribbon 42 is wound upon a roll 43, suitably supported on the machine frame. The feeding rollers 44 draw this 45 ribbon from the roll and deliver it to the guide chute 45. The rollers 44 are driven in any appropriate manner and in Fig. 3 I have shown a shaft 46 for this purpose furnished with bevel gears 47 and 48, the latter of which is driven by the gear 49 on the 50 main driving shaft.

It is to be understood that, for purpose of convenience, Fig. 3 has been greatly shortened so as to bring the roll 43 much closer to the binding unit than it would be in 55 practice. The particular location of these parts is, of course, not essential.

The cutting of the ribbon at the proper moment to provide suitable lengths for each package is accomplished by suitable cutting 60 mechanism 50 operated by a rod 51 whose movements are governed by a cutting cam 52 on the main driving shaft 53. The details of the cutting mechanism form no part of the present invention, and any automatic

cutter of well known construction may be 65 employed.

The ribbon grip is composed of a body 54 carrying a jaw 55 fixed to one side thereof and a second jaw 56 pivoted to the other side. The jaws are normally held together 70 by a spring 57, and they may be opened by a gripping catch 58, operated as herein-after described.

The grip carrier comprises a revoluble carrier body supporting a sliding frame 75 upon which the grip body 54 is carried. The carrier body preferably comprises two horizontal hollow sockets 59, 60, united by a rod 61 and fixed to a vertical shaft 62 revolubly mounted in a bearing guide 63. The shaft 62 is driven by a pinion 64 meshing with a pinion 65 on the same shaft with a gear wheel 66, which last is driven by a pinion 67 on the countershaft 68.

The sliding frame comprises a U-shaped rod 69 whose parallel legs enter the sockets 59 and 60 and are normally pressed outward by the springs 70, 71 (see Fig. 8). The gripper above described is carried on a rod 72 depending from the outer lower corner of 90 this frame, and a roller 73 on said frame bears constantly upon the guiding track 74. It will be clear from this description that, as the carrier body and frame are revolved together, the gripper carried by the latter 95 will be caused to follow a path the shape of which is determined by the shape of the track 74. This shape is shown in its preferred form in Fig. 3 in dotted lines.

As the gripper reaches the position shown 100 in Fig. 3, opposite the end of the ribbon emerging from the chute 45, the first "grip operator" comes into play. This element consists of a tripping stop 75 on the end of a tripping rod 76 commanded by a tripping 105 cam 77 on the main shaft. This stop is lifted at the proper moment in the path of movement of the catch 58, and, striking the inclined surface thereof, it separates the jaws 55 and 56. At this moment there is a 110 short pause in the movement of the gripper, due to omission of teeth at 78 in the driving gear 67; during which pause the extremity of the constantly moving ribbon 42 is projected between the jaws of the gripper (see 115 Fig. 3).

As soon as a sufficient length of ribbon has 120 been so projected, the travel of the gripper is continued, owing to the toothless portion of the gear 67 having passed the point of engagement with the pinion 66, and, the moment the catch 58 leaves the stop 75, the jaws close and grip the ribbon. Owing to the shape of the track 74, the gripper moves 125 inward toward the article 23, and thereby draws the ribbon across the outer face of the compression plate 31, over the flat top of the guiding projection 32.

As soon as the gripper has passed the plate 31, the "tension device" comes into operation. In the preferred form shown, this device comprises the tension plate 79 placed on the end of the flat guiding stem 80, which stem is provided with guiding slots 81 sliding on pins 82, and preferably formed, as shown, so that, as the stem and plate move upward, they will have first an inward movement toward the package and then a vertical movement into final position.

The action of the tension plate is to keep the ribbon suitably taut and level in proper position with respect to the package, which is determined by the guiding projection 32 on the plate 31. A similar projection 83 on the plate 79 acts as a guide for the second lap of the ribbon. The upward movement of the plate 79 is caused by the tension cam 84 on the main shaft, acting through a vertical stem 85 carrying an arm 86, to the outer end of which is pivoted the lower end of the guiding stem 80. The spring 87 acts to hold the stem 85 down on the cam 84.

After the operation just described, the gripper continues to travel around the package, drawing the ribbon along over the guide 32, under the tension plate 79, until the gripper again reaches about the position shown in Fig. 3, and the ribbon assumes the position shown in Fig. 6; at which time the gumming devices comes into operation. It will be seen by the dotted lines in Fig. 3 that, in the position shown, the gripper is about to move along an in-curving portion of the guiding track, whereby said gripper approaches the package more nearly than before. The object of giving this form to the track is to make the gripper bring the ribbon around the package to form the overlap, without drawing said ribbon any farther along under the tension plate. The shape of the track should be so calculated that, as the gripper approaches the package 23 it will not relax the ribbon, but will simply cause it to close in upon the package, while under normal tension. At the same time the rear extreme of the ribbon is held under the tension plate.

It is while the ribbon is thus stationary in that portion over the compressing plate 31 that the gumming device acts. This device may be of any well known character without departing from my invention, so long as it applies the gum and wipes the over-lap firmly over the gummed section of ribbon automatically. In the preferred form shown this element of the machine comprises two co-operating subordinate units; namely, the gum applying means and the wiping means for the overlap. These preferably have the following construction.

A gum reservoir 88 is placed near the

gumming point as shown in Fig. 3, and a gumming band 89 passes over two rollers; one, shown at 90 being within the body of gum, the other, shown at 91 being above the reservoir. This latter is slowly revolved, so as to drive the band 89 and bring a new supply of gum out of the reservoir. This may be accomplished by any appropriate means, as, for instance, by a belt 92 driven from a pulley 93 on the main shaft.

The gum is placed upon the ribbon by a gum transfer arm 94, pivoted at 95, and furnished with a roller 96 at its extremity, which is normally in the position shown in Fig. 3. The operative movement of this arm is indicated by the arrow in Figs. 6 and 3 and the dotted line position in Fig. 6 shows how the gum is applied by the roller 96 to the rear extremity of the ribbon, or near it. The operative movement just referred to is produced by the gumming cam 97 on the main shaft, acting through a push rod 98, pivotally connected to a rearward extension, 99, of the arm 94.

The movement of the arm 94 is a simple back and forth movement through the required circular arc, whereby the gum-covered roller 96 is passed over a suitable length of the ribbon. In order to prolong the period of contact, the roller 96 is mounted upon an extension 100 movable on the arm 94, and pressed outward by the spring indicated in dotted lines in Fig. 6. It is, of course, within the spirit of my invention to so shape the gumming cam as to cause a repeated movement of the arm 94 for each gumming operation.

This operation is completed just before the gripper brings the forward end of the ribbon around over the guide 32 on the tension plate and over the gummed section of ribbon, to form the overlap. Just after the gripper passes said gummed section, the ribbon wiping means and the second grip operator come into play. These act practically simultaneously, but in such manner that, when the ribbon is released by the gripper it finds a safe retaining agent in the wiping means. I, therefore, prefer that this latter means should operate just before action of the grip operator.

The wiping means preferably comprises a wiping arm 101, pivoted at 102 and carrying a wiping pad 103 at its extremity, which pad is spring mounted, as shown in Fig. 7, to extend the interval of contact with the ribbon and insure suitable firm yielding pressure. The arm 101 has an extension 104 to which is attached an operating rod 105, having a pinion 106, entering a suitable groove in the face of the wiping cam 107. The action of the arm 101 and rod 105 is indicated by the arrows in Fig. 7. This element wipes the pad 103 firmly once

forward upon the ribbon overlap, securing the same thereby to the previously gummed portion of the ribbon.

I prefer to arrange the wiping cam, in a well known manner, so that, after the forward wiping movement of the pad 103, the wiping arm does not return, until just after the package has been moved away from the binding unit.

10 The release of the ribbon is effected by means substantially like that already described for opening the jaws 55 and 56 in gripping the ribbon. The second tripping stop 108 is carried on a vertical rod 109, 15 commanded by a tripping cam 110 on the main shaft through a tilting arm 111. The stop moves upward into the path of the tripping catch 58 on the gripper in time to cause the ribbon release, and it then 20 drops back to normal position (see Figs. 1 and 2).

Finally the tension plate and the compression plates are withdrawn in that order each by a simple downward sliding motion 25 first, so that the fastening of the ribbon may not be disturbed. This is assured by the shape of the guiding slots 81 in Figs. 2 and 12, and by the appropriate action of the preparing cam 34 before release of the compressing levers 36. These latter are given 30 an extended vertical pressing surface for this purpose, as shown in Figs. 2 and 9. The resilience of the package causes it to swell sufficiently when released to insure a tight 35 hold of the ribbon whereby it will safely hold its proper position.

Upon completion of the binding operation as just described, the package may be removed from the machine by movement of 40 the bolt 20. Any desired means may be employed for this purpose, and in my aforesaid pending application, I have shown automatic means for this purpose, driven from the main driving shaft. As these means 45 form no part of the invention herein claimed, they are not described and illustrated more particularly in this specification.

It will be obvious to those skilled in machine construction that the many elements combined in this machine may be 50 arranged in a great variety of modified ways; and may, in many cases, be replaced by equivalents or modified forms, all without departure from the spirit of my invention and the scope of my claims. It is therefore to be understood that I do not limit myself to details of arrangement or construction save as specifically and explicitly set forth in my respective claims.

60 What I claim is—

1. In a package wrapping machine, a binding unit, comprising a ribbon conveyer adapted to grip a ribbon and carry it around the article to be wrapped, a gumming de-

vice, and automatic mechanism for operating said conveyer and gumming device in the proper order named, substantially as described.

2. In a package wrapping machine, a binding unit, comprising a gumming device, a package compressor, a ribbon conveyer adapted to carry a ribbon around said compressor while applied to the article to be wrapped, and automatic means for producing co-operative movements thereof, substantially as described.

3. In a package wrapping machine, a package holder, a ribbon conveyer, a tension device movable independently of said holder, a gumming device, and automatic means for producing co-operative movements of the same, substantially as described.

4. In a package wrapping machine, a package holder, a ribbon conveyer, a package compressor, a tension device movable independently of said holder, and a gumming device, and automatic means for producing co-operative movements of the same.

5. In a package wrapping machine, a package conveyer, a package holder, a compressor, and a ribbon conveyer, comprising a ribbon grip, and means adapted to cause said grip to move in a predetermined path around said holder and compressor, substantially as described.

6. In a package wrapping machine, a package holder, a closed guiding track, a part of which is placed farther away from said package holder than other parts, said track having an incurved portion approaching said package holder, a ribbon grip, and means for causing said grip to move around said package holder in a path conforming to said track, substantially as described.

7. In a package wrapping machine, a package holder, means for pressing a ribbon against a package, while in said holder, a device for dragging a ribbon between the package and said means, and means for causing said device to approach the package, and pressing means operating while the ribbon is stationary under the pressing means, substantially as described.

8. In a package wrapping machine, compressing plates, means for applying the same to a package, means for overlapping and securing a ribbon around said package while the compressing plates are so applied, and means for withdrawing said plates after operation of the means aforesaid, substantially as described.

9. In a package wrapping machine, a ribbon conveyer comprising a ribbon grip, a ribbon feed, for delivering a ribbon thereto, means for causing said grip to move around a package twice for each ribbon delivered by said ribbon feed, and means for causing said grip abruptly to approach said package,

each time the same passes a certain portion thereof, substantially as described.

10. In a package wrapping machine, a compressing plate, means for pressing the same against a package, means for drawing a ribbon around said package over said plate, and a tension device for pressing said ribbon against said plate, substantially as described.
- 10 11. In a package wrapping machine, a compressing plate, means for pressing the same against a package, a tension device, and means for drawing a ribbon over said plate under said tension device and then 15 over said tension device, substantially as described.

12. In a package wrapping machine, a compressing plate, means for pressing the same against a package, means for drawing a ribbon around a package over said plate, a tension device for pressing a ribbon against said plate, and means for withdrawing the plate and tension device, substantially as described.

25 13. In a package wrapping machine, a compressing plate, means for pressing the same against a package, a tension device, means for drawing a ribbon over said plate under said tension device, and then over 30 said tension device, and a gumming device, substantially as described.

14. In a package wrapping machine, a package supporting means, a ribbon grip, means for moving the same in an orbital path around said supporting means, and a stationary ribbon feed adapted to support the trailing end of a ribbon when drawn from it by said grip, substantially as described.

35 15. In a package wrapping machine, a package supporting means, a ribbon grip, means for moving the same in an orbital path around said supporting means, a stationary ribbon feed adapted to support the 45 trailing end of a ribbon when drawn from it by said grip, means near the point of delivery of said ribbon feed for operating said grip, and a second device at another point near the path of movement of said grip for 50 also operating the same.

16. In a package wrapping machine, a ribbon grip, a gumming device, and a wiping means; in combination with means for causing said grip to move around a package twice, and means near said gumming device for opening said grip, substantially as described.

55 17. In a package wrapping machine, a ribbon feed, a ribbon grip, and means for causing orbital movement of said grip; in combination with a device near the point of delivery of said ribbon feed for operating said grip, and a second device at another point near the path of movement of said

grip for also operating the same, both of 65 said grip-operating means being adapted automatically to come into play once for every two orbital movements of said grip, substantially as described.

18. In a package wrapping machine, a 70 ribbon grip, comprising jaws, normally in contact, means for imparting orbital movement to said grip, a grip operator normally disconnected from said grip and placed near the path of movement of said grip for opening said jaws, and means for moving said grip operator into and out of operative position, substantially as described.

75 19. In a package wrapping machine, a ribbon grip, comprising a body, a fixed and pivoted jaw thereon, a catch on said pivoted jaw, and a spring adapted normally to maintain contact between said jaws; in combination with means for imparting orbital motion to said ribbon grip, a grip operator 80 adapted to coöperate with said catch for opening said jaws, and automatic means for moving said grip operator into and out of operative position once for every two orbital movements of said grip, substantially as described.

85 20. In a package wrapping machine, a package holder, a grip carrier having a body revolubly mounted over said package holder, a ribbon grip on said carrier adapted to 95 move in the plane of the package, and automatic means for revolving said carrier and grip, substantially as described.

90 21. In a package wrapping machine, a grip carrier, comprising a revoluble body, and a sliding frame thereon; in combination with a guiding track extending around and outside of said frame, and means for maintaining contact between said track and said sliding frame, substantially as described.

100 22. In a package wrapping machine, a grip carrier, comprising two revolubly mounted horizontal sleeves, a sliding frame, having rods mounted in said sleeves, and springs in said sleeves for pressing said frame outward; in combination with a guiding track for limiting the outward movement of said frame, substantially as described.

105 23. In a package wrapping machine, a package holder, means adapted to convey a ribbon around said holder, in combination with a tension device comprising a tension plate, a guiding stem, and a tension cam adapted to move said tension plate across the plane of movement of said ribbon-conveying means, substantially as described.

110 24. In a binding unit of a package wrapping machine, a tension device, comprising a tension plate, a ribbon guide thereon, and means for moving said plate into and out of operative position against the package to be wrapped, substantially as described.

115 25. In a binding unit of a package wrap-

- ping machine, a tension device comprising a tension plate adapted to press against the article to be wrapped, a stem therefor having a slot bent in a plane directed across the 5 plane of the face of said plate, a pin extending into said slot, and means for moving said stem and plate up and down, substantially as described.
26. In the binding unit of a package 10 wrapping machine, a tension device, comprising a tension plate, a flat stem therefor, having a slot composed of two straight portions, forming an angle with each other, a pin coöperating with said slot for guiding 15 said stem, and means for raising and lowering said stem and plate, substantially as described.
27. In the binding unit of a package 20 wrapping machine, means for conveying a ribbon around said package, a tension device, comprising a tension plate, and means for moving the same into operative position against said ribbon, first in the direction inclined to the vertical and then in a vertical 25 direction, substantially as described.
28. In a package wrapping machine, a means for carrying a package, in combination with a package compressor movable independently of said carrying means, means 30 for applying a tying agent while said package is under compression, and means for moving said compressor away from the package, after application of said tying agent, substantially as described.
29. In the binding unit of a package 35 wrapping machine, a package holder, a package compressor movable toward and away from said holder, a ribbon conveyer, a gumming device, and means for removing 40 said compressor after application of a ribbon by said conveyer, substantially as described.
30. In the binding unit of a package 45 wrapping machine, a package holder, a package compressor movable toward and away from said holder, comprising preparing means, and compressing mechanism, substantially as described.
31. In a package wrapping machine, plates 50 adapted to be brought flatly into contact with opposite ends of the package, means adapted to wrap a ribbon around the package over said plates and automatic means for withdrawing said plates from under said 55 ribbon when in place, substantially as described.
32. In a package wrapping machine, a package holder, compressing plates adapted to move toward each other on opposite sides 60 of the package, means for moving said plates into and out of the plane of the package of
- said holder, and means for moving said plates inward against said package, substantially as described.
33. In a package wrapping machine, a 65 package compressor, comprising compressing plates, having ribbon guides; in combination with means for folding a ribbon around said plates over said guides, substantially as described. 70
34. In a package wrapping machine, a package compressor; having ribbon guides, tension plates having ribbon guides, and means for bringing said plates together with said guides, in line with each other, substantially as described. 75
35. In a package wrapping machine, movable sleeves, fixed guides therefor, compressing plates having horizontal rods, mounted slidably in said sleeves, and means for 80 raising and lowering said sleeves on said guides, substantially as described.
36. In a package wrapping machine, a package supporting means, a ribbon grip, means adapted to move said grip around said 85 package so as to overlap a ribbon on the package, and means for automatically securing said ribbon in place adapted to operate once for every two revolutions of said grip. 90
37. In a package wrapping machine, a lifting bar, lifting rods carried thereby, horizontal sleeves on said rods, compressing plates having rods mounted in said sleeves, and means for raising and lowering said 95 lifting bar, substantially as described.
38. In a package wrapping machine, compressing mechanism, comprising in combination, compressing levers, means for moving the same inward and outward with respect 100 to the machine, compressing members, and means for moving said compressing members into and out of the paths of movement of said levers, substantially as described.
39. In a package wrapping machine, compressing mechanism, comprising in combination, movable compressing levers having operating faces elongated transversely to the direction of movement of said levers, means for moving the levers inward and outward 105 with respect to the machine, compressing members, and means for moving said compressing members in the direction of elongation of the faces of said levers, substantially as described. 110
- In testimony whereof, I affix my signature, in presence of two witnesses.
